UNITED STATES PATENT OFFICE.

MEREDITH G. STANDLEY AND CHARLES W. GOSNELL, OF CINCINNATI, OHIO; SAID GOSNELL ASSIGNOR TO SAID STANDLEY.

HAND-STAMP.

1,206,766.

Specification of Letters Patent. Patented Nov. 28, 1916.

Application filed June 13, 1913. Serial No. 773,455.

To all whom it may concern:

Be it known that we, MEREDITH G. STANDLEY and CHARLES W. GOSNELL, citizens of the United States, residing at Cincinnati, 5 in the county of Hamilton and State of Ohio, have invented certain new and useful Improvements in Hand-Stamps, of which the following is a specification.

This invention relates to a hand-stamp 10 embodying the general principles of construction and operation disclosed and claimed in the pending application of Meredith G. Standley Serial No. 726,740, filed October 19, 1912.

15 One of the objects of the present invention is to provide an improved structural organization for relatively supporting the working parts in a manner to improve the efficiency of the operation, as well as enabling a simpler and more convenient manual manipulation of the stamp.

Another object of the invention is to provide means for feeding the record strip and inking strip rolls, an improved inking ribbon reversing mechanism; and to provide 25 means for most efficiently supporting and correlating these working elements to the structural elements of the stamp.

Another object of the invention relates to 30 means for mounting the printing disk and record rolls on one hinged member of the body, with the inking ribbon rolls, fixed printing surface and platen mounted on another hinged member of the body, so that 35 they are separably supported, enabling the record strip to be handled without inking the hands of the operator. This feature of the invention also enables a fixed and an adjustable printing surface to simultaneously impress the platen supporting the 40 article to be stamped, with the adjustable printing surface alone making an impression on the record strip, so that the step movement of the record strip need only 45 correspond to the dimensions of the adjustable printing surface.

Another object of the invention involves the provision of means whereby a single inking ribbon will serve for impressing the 50 adjustable printing surface on the record strip internal of the machine, and the article to be stamped when in position between the body and platen. The record and

inking ribbon strip are so correlated to one another and to the machine elements that 55 the type teeth of the printing disk are not inked directly, but operate by directly contacting the record strip, the record strip contacting the ribbon, which in turn contacts the article to be stamped, the record 60 strip being a transpicuous material so that the printing characters which are reversely impressed thereon may be read through the transpicuous record strip.

These and other features of the invention 65 will be more fully understood in connection with the description of the accompanying drawings forming a part of this specification and which illustrate the preferred embodiment of the invention.

In such drawings: Figure 1 is a side elevation view. Fig. 2 is a top plan view. Fig. 3 is a side elevation with the cover removed illustrating the paper feed. Fig. 4 is an end elevation. Fig. 5 is a side elevation with the cover removed showing the ribbon feed on the opposite side of the machine from that shown in Fig. 3. Fig. 6 is a cross sectional view taken longitudinally through the center of the machine. 70 Fig. 7 is a side elevation showing the machine in its open position. Fig. 8 is a plan view of the machine with the casing and racks removed. Fig. 9 is a detail view of the ribbon feed and reversing operating levers. Fig. 10 is a detail view showing the supporting and locking mechanism for the paper rollers. Fig. 11 is a longitudinal cross section taken through the lower portion of the machine and in its open position. Fig. 12 is a plan view of the machine portion as shown in Fig. 11. Fig. 13 is an end view of the machine as shown in Fig. 12. Fig. 14 is a central longitudinal section taken through the machine when in its 75 open position. Fig. 15 is a plan detail view of the frame carrying the type wheels and paper rolls. Fig. 16 is an end elevation view of the frame shown in Fig. 15, showing the outer cover and racks in cross section. Fig. 17 is a side elevation of the platen plate. Fig. 18 is a cross section on line 18-18, Fig. 3.

Structural elements and organization.—The stamp comprises a body or housing 1 100 and a platen plate 2 hinged together at one

end on the rod 3 (see Fig. 1) the working elements being supported within the body or housing 1, the article to be stamped being placed between the jaw-like members 1, 2 5 for receiving the impression.

The body 1 comprises several sub-structures, primarily a bottom plate 4 and a co-acting frame 5 (see Fig. 14) which are also relatively hinged on the rod 3, enabling 10 them to be opened up as shown in said figure.

The bottom plate 4 is formed with two pairs of bearing posts 6, 7, between which are rotatively supported the winding and 15 unwinding rolls 8 of the inking ribbon 11. Said plate 4 is orificed at 9, (see Fig. 6), opposite the platen block 10, of plate 2, through which the type disk operates to impress the article to be stamped. The inking 20 ribbon 11 is threaded through orifices 12, of plate 4, so as to pass from the interior to the exterior of said plate, passing over a fixed printing surface 13, at one side of orifice 9, enabling the fixed and adjustable printing 25 surfaces to be simultaneously impressed on the article to be stamped, while for impressing the adjustable printing surface on the record strip, the inking ribbon and record strip need only be fed in small step movements, the dimensions of which are appropriate to those of the printing disk type teeth prescribed in stamping position, see Fig. 6.

The upper frame 5, which is hinged relative to plate 4, comprises the U-shaped top piece 14, (see Figs. 15 and 16) formed with the orifice 17, through which the top of the type disk passes, the countersunk portion 18, of piece 14, supporting the disk operating racks, said frame 5 having the side walls 19, 20. The type disks 21 are journaled between walls 19, 20, and the record rolls 22 are also journaled between walls 19, 20, on opposite sides of the printing 45 disks. The transpicuous record sheet 23 passes over the lower periphery of the type disks, so that when members 4 and 5 are closed, the parts occupy the serial positions, shown in Fig. 6, type disks, contacting 50 record strip 23, and externally contacting inking ribbon 11, pressed through orifice 9, the adjacent portion of the inking ribbon passing over the fixed printing surface 13, so that both surfaces will contact an article 55 on platen block 10, in stamping. Thus the ribbon serves for printing both surfaces on the article to be stamped, outside of plate 4, and for printing the record strip with printing disk characters; the inking rolls 60 need be only fed in small step movements to draw the same across the peripheries of the printing disks; and the type teeth are covered by the record strip so as not to contact the inking ribbon. At the same time, 65 opening up members 4 and 5 separates the

record and inking strip rolls, so that the record can be removed without inking the hands of the operator, or smearing the printed record of the strip.

The rack bars 24 lie in the trough 18, and are longitudinally movable in the tangential plane of the peripheries of the type disks, with the type teeth 25 of which the rack teeth 26 intermesh.

The frame member 5 is inclosed by cover 27, having its top plate 28, (see Fig. 2), formed with longitudinal slots 29, through which project the headed pins 30 of the racks 24, so as to suspend the said bars from the cover, the bars being adjusted to move the printing disks to selected printing position, by sliding said pins 30 in their longitudinal slots. Top plate 28 has also a transverse aperture 31, through which are exposed in aligned position the characters 32 on the upper faces of bars 24, representing corresponding type disk characters in stamping position.

On the under side of plate 14 is secured a series of leaf springs 33, having knob or cam-like free ends 34, projecting upwardly through orifice 17 and engaging between rack teeth 26, to impart step movements to their adjustment, and to urge them to definite step movements to bring the type teeth accurately into invariable printing position.

Thus it will be seen that members 2, 4, and member 5, carrying cover 27, are all hingedly connected together on rod 3, rendering a very efficient operation, and an easy and convenient manipulation of the organized stamp, when any attention is to be given to the mechanism housed within the body 1.

The side pieces 19, 20, of frame 5, afford convenient provision for supporting the inking ribbon feed and reversing mechanism, and the record feeding mechanism on the other side of the stamp, exterior of said frame 5, and protected by the side walls 35 of the cover 27, while the means for detachably supporting the record strip rolls are mounted on the inner walls of side pieces 19, 20, of frame 5, the inking ribbon rolls being supported on plate 4, as before explained.

Record strip feed mechanism.—In Fig. 3, a side elevation of side piece 19 is shown with the record feed mounted thereon. From plate 2, a post 36 is projected upwardly through plate 4, against which the prime mover of the feed mechanism is movably engaged in the act of stamping, to actuate the feed. The rear feed roll 22 of the record strip has a shaft 37, having the detent 38 at one end. A ratchet wheel 39 is journaled between the outer face of said piece 19, and a bracket plate 40, secured to said piece, the stub shaft of said ratchet wheel being projected through said piece 19 and having an 125

indent 41 for engaging detent 38, to rotatively connect said ratchet wheel and the record strip roll. The corresponding end of the shaft 42 of the other record roll 22, is projected through piece 19, and a friction wheel 43 is fixed thereto, the outer end of said shaft bearing in bracket 40. The prime mover of this feed is a lever 44, fulcrumed at 45, and having a longitudinal limb 46, and a downward extension 47, engaging post 36 for actuating said lever. A spring 48 connects the free end of said lever with the frame, pressing said lever normally downwardly, and yielding under pressure to permit said lever to rise in the act of stamping. Pivoted to the free end of lever 44, is a pawl 49, the end of which engages the teeth of the ratchet wheel 39, said pawl being forced inwardly against the wheel by spring 50, connected to lever 44, and the pawl finger 51. The movement of winding wheel 39 is held under tension by spring 52, and spring 53 imposes friction on the unwinding friction wheel 43. It will thus be seen that the pressing together of members 1 and 2, raises lever 44, which returning under spring tension, actuates the pawl and ratchet mechanism to feed the record strip a definite and appropriate step interval.

The method of detachably supporting the record strip rolls, is shown in Figs. 3 and 10, wherein piece 20 is formed with open slots 54 for the shaft ends of the record rolls. One end of the type disk shaft 55, has a bearing-in piece 20, and the other end a bearing-in piece 19. A bridge plate 57 has slotted connection 56 to piece 20, having lugs and slots 58, 59, transverse to the slots 54, for detachably securing the ends of the record roll shafts to the piece 20, the other ends of said shafts being inserted in fixed bearings in piece 19. In this way, the record rolls can be removed or inserted, without disturbing the printing disk support or the mounting of the inking ribbon rolls.

Inking feed and reversing mechanism.—This mechanism is mounted on the outer face of side piece 20 of the frame 5, being shown assembled in Fig. 5, and the detail in Fig. 9. An ink ribbon feeding post or abutment 60 is projected from plate 2, through bottom plate 4, in position to be engaged by the prime mover of the ribbon feed and actuated by the stamping act. The prime mover is a lever 61, fulcrumed at 62, its moving end being connected to the frame by spring 63, forcing it normally downward. At the free end is a pawl 64, engaging the rack teeth of a ratchet wheel 65, fixed to one of the inking ribbon rolls, said pawl being urged normally inward by spring 66, when the pawl is positioned for feeding. A similar lever 67, lies over lever 61, fulcrumed at 68, said levers extending in opposite directions. At the moving end of lever 67 is a spring 69, con-

necting it to the frame, and also a pawl 70, urged toward ratchet wheel 71, of the other inking roll, by means of spring 72, when this pawl is in position for feeding. The pawls are alternately engaged and disengaged from their respective ratchet wheels for feeding the ribbon in step movements, a predetermined distance each way. A plate 73 is pivoted to lever 61 at 74, and to lever 67 at 75, and said levers have medial contact at 76, so that they will move in unison. A reversible pawl trip 77 is pivoted at 78, to plate 73, said trip fulcrum point moving in a vertical plane because of said lever connections. Said trip has a right-hand finger 79, 80 engaging pawl 64, and a left-hand finger 80, engaging pawl 70, to function the pawl and ratchet wheel appropriate to the position of trip 77 on plate 73. Said trip is shifted by the engagement of its downward projected dogs 81, 82, with the sliding dogs 83, 84, of the base plate 4, (see Fig. 7). Said dogs 83, 84, are carried by a slide 85, at one side of plate 4, the slide having end abutments 86, adjacent the inking ribbon rolls, and at 90 one edge of the ribbon. In each end of the ribbon is a transverse pin 87, extended at 88, to project beyond the ribbon in position to engage the abutments 86, see Fig. 12.

On trip 77 is a latching finger 88, snapping frictionally over a slight detent 89, on plate 73, for holding trip 77 in its adjusted position between reversing operations. As shown in Fig. 5, the ribbon is feeding to the right, moving one step for each downward movement of the lever 61, the pawl being held in commission by the position of the trip 77. When the ribbon has been unwound from the left-hand roll, the left roller pin will strike abutment 86 and shift the slide 85, bringing dog 83 into position to be engaged by dog 82, of trip 77, so that the upward movement of trip 77 shifts or reverses the tilt of said trip, throwing the right-hand pawl out of, and the left-hand pawl into commission. At the end of the feed of the ribbon to the left, the pawls will be reversed by the engagement of the other trip dogs 81 and 84.

We preferably employ a lock 90, (see Fig. 115 4) at the moving end of the stamp, to hold together the structural elements of the body member 1, the key being retained by the proper office man, so that the record is inaccessible to the collector or user of the 120 stamp..

It will thus be seen that we have produced a pocket type of stamp, the working elements being compacted into a small space, the operation being simple and efficient. 125

The method of separably supporting the record and inking ribbon rolls, and of bringing them together in the correlation for stamping is a particular advantage, as is also the provision of a transpicuous record 130

strip for protecting the type teeth from ink contact, and yet serving to receive a legible record.

The principle of invention may be variously modified within the scope of the claims which are not limited to specific details, except wherein they are directly recited.

Having described our invention, we claim:

- 10 1. A stamp comprising a box-like casing body and a coextensive platen plate coacting with the said body, a hinged plate forming the bottom of the casing body adjacent the platen and apertured for stamping a printing-wheel, ink-ribbon rolls, record rolls adapted to support an inking ribbon and a record strip, respectively, and feeding mechanism within the casing body, the wheel periphery projecting through the bottom plate of the casing, enabling the ribbon and record strip to pass over this portion of the wheel within the casing body, wheel positioning and indexing mechanism disposed and operating in the tangential plane of the 25 wheel in the upper portion of the casing body and operatively accessible through the upper side of the casing body, and said wheel, inking ribbon and record strip rolls, being separably mounted on the bottom plate 30 of the casing and within the casing, enabling them to be opened up when said bottom plate is opened relative to the casing body.
- 35 2. A stamp comprising a box-like casing body, a printing-wheel therein, the body width and wheel diameter being approximately equal, wheel operating means accessible through the upper portion of the casing the bottom of the casing body, inking 40 tial plane of the wheel, a hinged plate forming the bottom of the casing body, inking ribbon and record strip rolls adapted to support an inking ribbon and record strip, respectively, said wheel and rolls being separably mounted on the hinged plate and with- 45 in the casing body, inking ribbon and record strip feed mechanism within the casing, supported by the inner walls thereof, normalizing means for said body and casing, and means enabling a relative movement of said 50 body and platen to actuate said feed mechanism.
- 55 3. In a stamp, an orificed plate and frame separably connected to form a housing, a printing wheel, record strip supports on opposite sides of the wheel, enabling a record strip to pass around its supports and over the printing wheel periphery, said members being supported in the frame, rolls bearing an inking ribbon on the plate, a 60 fixed printing surface carried by the plate upon one side of the peripheral printing surface of the wheel projecting through the plate orifice, the inking ribbon passing over the fixed printing surface and over the portion of the record strip directly contacting

the adjustable printing surface for simultaneously impressing the fixed and selected printing surfaces on the article to be stamped under the plate, and impressing the selected printing surface on the record strip 70 within the housing.

4. In a stamp, an orificed plate and frame separably connected to form a housing, feed rolls forming a support for a record strip, and a printing wheel supported between 75 walls of the frame, a record roll feed mechanism on the outside of one wall of the frame, an inking roll feed mechanism on the outside of the other frame wall, supports for inking ribbon rolls and an inking ribbon on 80 the plate, the rolls and wheel axles being substantially parallel within the housing, ratchet wheels on the ends of the inking roll shafts operatively connected with the ribbon feed and reversing, mechanism when the 85 housing is closed, the printing periphery of the wheel, the contacting record strip and the ribbon being serially disposed and projecting through said plate orifice, and means for actuating said feed mechanisms actuated 90 by the stamping.

5. A stamp comprising a box-like casing body, a printing wheel therein, inking ribbon and record strip rolls adapted to support an inking ribbon and a transpicuous 95 record strip respectively in the casing, a separable bottom plate for the casing body, apertured adjacent the wheel, an inking ribbon contacting the record strip, and a platen adjacent the inking ribbon, for simultaneously impressing the printing surface of the printing wheel on the article to be stamped on the platen and the transpicuous record strip between the inking ribbon and printing surface.

6. A stamp comprising a relatively movable box-like casing body and platen plate, a separable bottom plate for said body apertured for stamping on the platen, record rolls adapted to support a transpicuous 100 record strip, and a printing wheel and inking ribbon rolls adapted to support an inking ribbon, said rolls being substantially parallel, the record rolls having their inner members adjacent the opposite sides of the wheel, the ribbon rolls being the outer members, the transpicuous record strip winding and unwinding on the record rolls and directly contacting the periphery of the printing wheel, an inking ribbon on its rolls with one portion thereof contacting the portion of the record strip contacting the printing wheel, and a platen adjacent the said portion of the inking ribbon.

7. In a stamp, a housing body and coacting platen plate, a type disk, the vertical dimensions of the body and disk diameter being approximately the same, a separable bottom plate for the body through which the disk projects for stamping, inking and 125 130

record strip supporting rolls in said body, means for operating said rolls by the stamping operation, a fixed printing surface supported by the bottom plate of the body adjacent the disk periphery, said fixed and disk printing surfaces being flush and operating with relation to the platen, and means enabling the printing surfaces to be impressed upon the article to be stamped, and only the disk characters to be impressed on the record strip.

8. In a stamp, a housing body and coacting platen plate, a type disk, the vertical dimension of the body and disk diameter being approximately the same, a separable bottom plate for the body through which the disk projects for stamping, inking and record strip rolls adapted to support an inking strip and record strip respectively rotatable in said body, means for feeding said strips through the stamping operation, a fixed printing surface supported by the bottom plate of the body adjacent the disk periphery constituting a selective printing surface, said fixed and selective printing surfaces being flush and operating with relation to the platen, and means enabling both printing surfaces to be simultaneously impressed upon the article to be stamped, and impressing only the selective character on the record strip in coaction with said printing platen.

9. In a stamp, an orificed plate and frame hinged to form a housing when closed, a printing wheel, record support rolls on opposite sides thereof positioned to engage a record strip with the printing periphery of

the wheel, said members being mounted in the frame, inking ribbon support rolls mounted on the plate and positioned to enable the ribbon to bridge said plate orifice and to contact the record strip when the housing is closed, a feed mechanism for the record support rolls on the outer face of one wall of the frame, a feed and reversing mechanism for the inking ribbon support rolls on the outer face of another wall of the frame, said feed mechanisms being operative when the housing is closed, and means for actuating said feeding and reversing mechanism by the stamping movement.

10. In a stamp, two separable members constituting a housing, a platen member coacting therewith, record strip support rolls, inking ribbon support rolls, and a printing wheel mounted in said housing, said rolls and wheel being in substantial alignment, the record and inking ribbon rolls being separably carried by said members, the printing wheel, record strip rolls and ribbon rolls being arranged and positioned to tangentially project the record strip and ribbon through said housing adjacent the platen for stamping, feed mechanism for said rolls, and means for automatically operating said mechanisms in stamping.

In testimony whereof, we have hereunto set our hands.

MEREDITH G. STANLEY.
CHARLES W. GOSNELL.
